UNITED STATES PATENT OFFICE.

CHARLES B. MEAD AND ROBERT S. FULLERTON, OF EAST PALESTINE,
OHIO, ASSIGNORS OF ONE-THIRD TO JAMES V. MURPHY, OF EAST
PALESTINE, OHIO.

CAR-BRAKE.

No. 823,285.

Specification of Letters Patent.

Patented June 12, 1906.

Application filed February 28, 1906. Serial No. 303,344.

To all whom it may concern:

Be it known that we, CHARLES B. MEAD and ROBERT S. FULLERTON, citizens of the United States of America, residing at East Palestine, in the county of Columbiana and State of Ohio, have invented certain new and useful Improvements in Car-Brakes, of which the following is a specification, reference being had therein to the accompanying drawings.

This invention relates to certain new and useful improvements in car-brakes; and the invention relates more particularly to brakes adapted to be used in connection with street-cars.

The primary object of this invention is to provide a novel form of brakes for street-cars which are thrown into operation when the car becomes uncontrollable or should it be desired to quickly stop a car.

Our invention aims to provide a car-brake which will be extremely simple in construction, strong and durable, comparatively inexpensive to manufacture, and highly efficient for the purposes for which it is used. The car-brake is constructed whereby it may be operated from either end of a car to brake either one of the trucks thereof, and in this connection the brakes serve functionally as chock-blocks for retarding the forward or rearward movement of a car, said blocks engaging the periphery of the wheels of the trucks and the tread of the rails upon which the wheels move.

The detail construction entering into our invention will be hereinafter more fully described and claimed, and, referring to the drawings accompanying this application, like numerals of reference designate corresponding parts throughout the several views, in which—

Figure 1 is a side elevation of a car equipped with our improved brakes. Fig. 2 is a fragmentary plan of the trucks thereof, illustrating our improved brakes. Fig. 3 is a perspective view of one of the shoes of the brakes; and Fig. 4 is a plan of one of the shoes, illustrating a slightly-modified form of construction.

In the accompanying drawings we have illustrated a conventional form of car 1, supported upon trucks 2 and 3, said trucks being

of the ordinary type commonly employed in connection with street-cars. In the present illustration we have shown the trucks and car mounted upon the rails 4 of a track, and in connection with these rails and the trucks of a car we use our improved brake. 55

The brake consists of four blocks 5 5 and 5' 5', two blocks being used in connection with each truck, preferably upon the inner wheels thereof. The body portion of each block is preferably constructed of iron or steel and is provided with a curved surface 6 and a flat surface 7. The curved surface 6 of each block is recessed, as at 8, to accommodate the curved end 9 of a shoe which is adapted to fit upon each block. The shoe is provided with a straight portion 10, adapted to fit upon the flat portion 7 of each block, and with a right-angular extension 11, adapted to engage the rear face of the block. The shoes are preferably constructed of case-hardened steel and are secured to the blocks by screw-bolts 12 12, passed through the right-angular extensions 11 into the blocks 5. The lower faces of the shoes are serrated or knurled, as at 14, the serrations adjacent the curved ends 9 of the shoes being of a finer degree than the remainder of the serrations, the object of 80 which will be presently described. In lieu of the serrations 14 the lower face of the shoe may be notched or roughened, as at 15; but the mode of roughening the shoes is immaterial so long as a gripping-surface is provided upon said shoes. 85

The blocks 5 5 and 5' 5' are connected together by transverse shafts 16 and 17, said shafts being suspended by links 19 19 from brackets 20 20, carried by the trucks 2 and 3. 90 The blocks 5 5 and 5' 5' are further supported by rods 21 and 22, said rods extending to the ends of the car, where they are pivotally connected to operating-levers 23 and 24, respectively. The operating-levers are pivotally mounted upon shafts 25 25, mounted in depending brackets 26 26, carried by the car 1.

The rods 21 and 22, together with the links 19, support the blocks 5 5 and 5' 5' in an elevated position in close proximity to the inner wheels of the trucks 2 and 3, and the particular shape of said blocks permits of a portion of the shoes carried by said blocks ex-

tending beneath the wheels in close proximity to the rails 4, upon which the tracks 2 and 3 move. Assuming that the car is moved to the left and has become uncontrollable, the operating-lever 23 is manipulated to lower the blocks 5' 5'. These blocks are adapted to simultaneously impinge the wheels of the truck 3 and the rails 4, the curved surfaces 6 of said blocks engaging the peripheries of the wheels of the truck 3, while the serrated surfaces 14 of the shoes of said blocks engage the treads of the rails 4, over which the trucks move. The serrated surfaces 14 of the shoes are adapted to engage in the treads of the rails 4 and prevent said shoes from sliding upon said rails, especially when the shoes and blocks 5' 5' are engaged by wheels of the truck 3. By providing the innermost ends of the shoes with finer serrations than the outer ends a more positive grip is taken upon the treads of the rails immediately upon the blocks 5' 5' being lowered, and when the wheels of the truck 3 ride upon said blocks the entire serrated surfaces of the wheels of said trucks will be forced into engagement with the rails, and the car equipped with the brakes will be brought to a speedy standstill.

The blocks 5 5 are operated in connection with the truck 2 when the car is going in a reverse direction to that just described, and the operating mechanism of said blocks is similarly manipulated to the operating mechanism of the blocks 5' 5'.

We do not care to confine ourselves to the specific shape of the blocks of our improved brakes, but attach considerable importance to the shoes carried by said brakes.

Such changes as are permissible by the appended claims may be resorted to without

departing from the spirit and scope of the invention.

What we claim, and desire to secure by Letters Patent, is—

1. In a car-brake, the combination with a car, and the trucks thereof, of blocks suspended from the trucks of said car in close proximity to the wheels of said truck, serrated shoes carried by said blocks, said shoes having each an upwardly-extending curved end engaging the front face of the block and a right-angular extension engaging the rear face of the block and means operated from the ends of said car to move said shoes into engagement with said wheels, and the rails upon which said wheels travel, substantially as described.

2. In a car-brake, the combination with the trucks and wheels upon which the trucks are mounted, of a plurality of brackets carried by each truck, links pivotally mounted in said brackets, a shaft carried by the links of each truck, blocks mounted on the ends of each of said shafts, shoes carried by said blocks and adapted to contact with the wheels and with the tracks, a rod connected to the shoe-carrying shaft of each truck and extending over the shoe-carrying shaft of the adjacent truck, and operating the levers connected to said rods and extending from below the bottom of the car to above the bottom of the same, substantially as described.

In testimony whereof we affix our signatures in the presence of two witnesses.

CHARLES B. MEAD.
ROBERT S. FULLERTON.
